Control Products, Inc., Coopersville, Mich., a corpora-
tion of Michigan

Filed Apr. 16, 1958, Ser. No. 729,020

3 Claims. (Cl. 98—37)

This invention relates to ventilating means for attics 10
including roof and soffit ventilator members.

The main objects of this invention are:

First, to provide an attic ventilating means including
soffit ventilator members which may be very quickly and
easily installed as a unit and adds to the appearance of
the eaves.

Second, to provide an elongated soffit ventilator member
which presents a smooth upper surface and may be formed
of relatively thin material such as sheet aluminum, for
example, and at the same time is substantially rigid.

Third, to provide an elongated soffit ventilator member
having a plurality of longitudinally spaced louvered venti-
lator openings.

Objects relating to details and economies of the inven-
tion will appear from the description to follow. The 25
invention is defined in the claims.

A structure which embodies the features of the invention
is clearly illustrated in the accompanying drawing, in which:

FIG. 1 is a diagrammatic end elevation view of the
upper portion of a building embodying the invention, the
direction of circulation of air being indicated by arrows.

FIG. 2 is a fragmentary perspective view of a portion
of a building embodying the invention.

FIG. 3 is a fragmentary vertical section on a line corre-
sponding to line 3—3 of FIG. 2.

FIG. 4 is a fragmentary side view of one form of my
improved soffit ventilator member.

FIG. 5 is a fragmentary perspective view thereof in
transverse section.

FIG. 6 is a side view of another form or embodiment
of the invention, the modification being in the stiffening
or reinforcing features.

FIG. 7 is a fragmentary perspective view of the embodi-
ment shown in FIG. 6.

FIG. 8 is a side view illustrating another modification
of the invention, the modification being in the stiffening
means.

FIG. 9 is a fragmentary perspective view of the embodi-
ment shown in FIG. 8.

In the accompanying drawing, 1 represents the wall of a
building, 2 the roof thereof and 3 an attic. The roof pro-
jects beyond the side wall forming eaves of substantial
width and having a front or facia member 4 which has a
downwardly projecting edge portion 5, that is, it projects
downwardly beyond the soffit frame pieces, only one of
which is shown at 6. It will be understood that these
structural features of the building are greatly varied in
practice; therefore, they are shown mainly conventionally
in the accompanying drawing.

In the structure illustrated the front edge 7 of the soffit
member 8 is spaced from the lower edge of the eaves face
member 4 and the space between these members is closed
by the elongated soffit ventilator member 9 which may be
desirably formed of a strip of sheet aluminum stock al-
though it may be economically formed of stainless steel
or plastic. The soffit ventilator member 9 is provided
with longitudinally spaced louvered openings 10, the
louvers 11 being struck downwardly from the plane of the
ventilator member and being rearwardly inclined so that
the louvers serve as guards to minimize the entrance of
water and snow and to check wind.

2

In the preferred embodiment the louvered openings are
surrounded by downwardly projecting rectangular beads
12 which stiffen the ventilator member both transversely
and longitudinally but they are spaced so as to permit the
securing of the ventilator member by means of nails or
other fastenings indicated at 13. Nails or like fastenings
may be driven through the ventilator member and into
some supporting part such for example as joists. The
ventilator member is not provided with preformed holes
for the reason that it is produced in strips of substantial
length and cut to particular requirements, and the pos-
itioning of the support members in relation to each other
varies greatly in different buildings.

The embodiment of the invention shown in FIGS. 6
and 7 is the same as that shown in FIG. 5 with the ex-
ception that the reinforcing ribs or beading 12 surround-
ing the louvered openings is omitted and the longitudinal
edges are conformed to provide downwardly projecting
beadlike reinforcing ribs 14. It should be understood that
these ribs or beads 14 are continuous.

The embodiment shown in FIGS. 8 and 9 is the same
as that shown in FIGS. 6 and 7 with the exception that
the longitudinal edges of the soffit ventilator member
have downturned flanges 15 instead of the beaded rein-
forcing member 14 of FIGS. 6 and 7. The structure of
FIGS. 8 and 9 is somewhat more economical to produce
than that of FIGS. 6 and 7 in the matter of forming and
it would require slightly less stock. The structure illus-
trated in FIGS. 6 and 7 requires somewhat more stock
than the preferred embodiment in which the rectangular
reinforcing ribs and the louvered openings may be formed
simultaneously by forming dies.

These soffit ventilator members are adapted for use
in widely varying building structures. I am aware that
it is old to install soffit ventilators in openings especially
formed therefor in eaves, that is, the openings are especial-
ly designed and spaced to receive the soffit ventilators.
The continuous strip or elongated soffit ventilator of this
invention merely requires that the soffit member 6 be of
such width as to permit the positioning of the soffit ven-
tilator member between it and the eaves face member or a
longitudinal opening left in the eaves at any point of
suitable width to receive the ventilator member.

The roof ventilator conventionally illustrated at 16 is
desirably positioned at an elevated point in the roof.

I have not attempted to illustrate various adaptations
as it is believed the disclosure made will enable those
skilled in the art to adapt the invention as may be desired.

Having thus described the invention what is claimed as
new and desired to secure by Letters Patent is:

1. A building including an attic, and a roof having
eaves including a front member and a soffit member the
front edge of which is in inwardly spaced relation to said
front member providing an elongated opening therebe-
tween, and an elongated soffit ventilator member dis-
posed in said elongated opening and constituting a closure
therefor, said soffit ventilator member having a plu-
rality of longitudinally spaced louvered openings there-
in, the louvers extending longitudinally of said ventilator
member and being disposed in forwardly projecting in-
clined relation to the plane of the body portion thereof,
said ventilator member having a downwardly projecting
bead-like rib surrounding each group of said louvers, said
ribs constituting reinforcing and stiffening means for said
soffit ventilator member, the roof having an air ventilator
disposed at an elevation substantially above that of the
said soffit ventilator member.

2. A building including an attic, and a roof having
eaves including a front member and a soffit member the
front edge of which is in inwardly spaced relation to said
front member providing an elongated opening therebe-
tween, and an elongated soffit ventilator member disposed

in said elongated opening and constituting a closure therefor, said soffit ventilator member having a plurality of longitudinally spaced louvered openings therein, the louvers extending longitudinally of said ventilator member and being in forwardly inclined relation to the plane of the body portion thereof, the roof having an air ventilator disposed at an elevation substantially above that of the said soffit ventilator member.

3. An elongated unitary soffit ventilator member having a plurality of longitudinally spaced louvered openings therein with the louvers extending longitudinally thereof and in forwardly inclined relation to the plane of the body portion thereof, said soffit ventilator member having a downwardly projecting bead-like rim surrounding each group of said louvers and constituting reinforcing and stiffening means for the ventilator member. 15
